CLAIM

We claim the ornamental design for a re-useable shipping tag for baggage, as shown and described.

DESCRIPTION

FIG. 1 is a rear perspective view of a re-useable shipping tag for baggage, showing our new design, here with a tongue and strap in a closed configuration.

FIG. 2 is a front perspective view thereof.

FIG. 3 is rear plan view thereof.

FIG. 4 is a right side elevation thereof.

FIG. 5 is a left side elevation thereof.

FIG. 6 is an elevation viewed from the end distant from the tongue and strap thereof.

FIG. 7 is an elevation viewed from the end nearer the tongue and strap thereof.

FIG. 8 is a front plan view thereof.

FIG. 9 rear perspective view of a re-useable shipping tag for baggage, showing our new design, here with said tongue and strap in an open and extended configuration; and,

FIG. 10 is a front perspective view thereof with said tongue and strap in the open and extended configuration.

Diagonal surface shading shown within rectangular frames in Drawing FIGS. 1 to 3 and 8 to 10 represents transparent windows. Broken line in those views represents stitching.
